The ornamental design for a cabinet light, as shown and described.

DESCRIPTION

FIG. 1 is a top, front, right side perspective view of a cabinet light, showing our new design;

FIG. 2 is a bottom, rear, left side perspective view thereof;

FIG. 3 is a front elevational view thereof;

FIG. 4 is a rear elevational view thereof;

FIG. 5 is an enlarged right view thereof;

FIG. 6 is an enlarged left view thereof;

FIG. 7 is a top plan view thereof;

FIG. 8 is a bottom plan view thereof;

FIG. 9 is an enlarged view of the portion 9 in FIG. 1;

FIG. 10 is an enlarged view of the portion 10 in FIG. 2; and,

FIG. 11 is an enlarged view of the portion 11 in FIG. 2.

The evenly dashed broken lines illustrate portions of the cabinet light and form no part of the claimed design. The unevenly dashed broken lines define the boundaries of enlarged views and form no part of the claimed design.
